UNITED STATES PATENT OFFICE.

THOMAS F. BURNS, OF OKLAHOMA, OKLAHOMA, ASSIGNOR OF ONE-HALF TO R. E. CRUISE,
OF OKLAHOMA, OKLAHOMA.

DEMOUNTABLE RIM.

1,247,789.

Specification of Letters Patent.

Patented Nov. 27, 1917.

Application filed November 22, 1916. Serial No. 132,854.

To all whom it may concern:

Be it known that I, THOMAS F. BURNS, a citizen of the United States, residing at Oklahoma, in the county of Oklahoma and State of Oklahoma, have invented a new and useful Demountable Rim, of which the following is a specification.

It is the object of the present invention to provide novel means for locking a demountable rim to the felly of a vehicle wheel.

The invention aims to provide novel means whereby a circumferentially movable ring may be made effective to hold the demountable rim on the felly, and to provide novel means whereby, when the said ring is actuated, the same will start the demountable rim transversely off the felly.

The invention aims to improve generally and to enhance the utility of devices of that type herein disclosed.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:

Figure 1 shows in top plan, a device constructed in accordance with the present invention, a portion of the demountable rim appearing in section;

Fig. 2 is a cross section on the line 2—2 of Fig. 1;

Fig. 3 is a fragmental longitudinal section;

Fig. 4 is a fragmental side elevation showing a wheel rim embodying the present invention; and

Fig. 5 is a cross section taken approximately on the line 5—5 of Fig. 1;

Fig. 6 is a fragmental cross section showing the manner in which the wedge on the lug of the locking ring engages beneath one end of the rib on the demountable rim; and

Fig. 7 is a side elevation showing that portion of the ring which carries the locking wedge shown in Fig. 6.

The numeral 1 designates a felly having side flanges 2 and 3. The side flange 3 is

provided with a notch 4. A pair of recesses 5 and 6 are fashioned in the felly 1. The felly 1 has a circumferential groove 7 located near the side flange 3. Mounted to rotate circumferentially of the felly 1 in the groove 7 is a ring 8 which preferably is continuous. The ring 8 has an upstanding lug 9, the inner face of which is inclined as shown at 10. The lug 9 has a wedge 90 on its inner side. The wedge 90 slopes in a direction parallel to the median plane of the wheel. Mounted on the felly 1 is a spring 11 held in place by securing elements 12. The spring 11 may be of any desired form, one end of the spring bearing on one end of the lug 9. The function of the spring 11 is to rotate the ring 8 in the direction of the arrow A. The ring 8 is provided on its under surface with a rack 14. A pinion 15 is located in the recess 5 and meshes into the rack 14. The pinion 15 is carried by a transverse shaft 16 journaled in the felly 1. One end of the shaft 16 is accessible from the exterior of the felly 1 and terminates in a squared portion 17 adapted to receive a wrench or key (not shown). Mounted to slide in the recess 6 is a dog 18. The dog 18 is advanced by a compression spring 19 located in the recess. The dog 18 has a depending stem 50 mounted to move in the slot 51 in the felly 1. The stem 50 is provided with an angular arm 52 terminating in a button 20. The dog 18 is adapted to engage a notch 53 in the ring 8. The felly 1 has transverse ribs 24. At 25 there appears a demountable rim carrying a tire 26. The demountable rim 25 has a transverse rib 27 received between the ribs 24 on the felly 1. One end of the rib 27 is inclined as shown at 28 to coöperate with the inclined edge 10 of the lug 9 on the ring 8. The inclined end 28 of the rib 27 has a recess 92 which receives the wedge 90. A lever 29 is fulcrumed at 36 on the felly 1. The lever 29 includes an arm 30 and an arm 31. The arm 31 lies between projections 32 and 33 on the ring 8. The arm 30 coacts with the projection 35 on the demountable rim 25. There is a slot 34 in the flange 3, through which the projection 35 may pass.

The structures above described may be duplicated any desired number of times around the circumference of the felly 1.

Let it be supposed that the demountable

rim 25 is locked on the felly 1. Then the co-operation between the parts is as follows:—

The rib 27 of the demountable rim 25 abuts at one end against the side flange 2 of 5 the felly 1 as shown in Fig. 1, and is received between the ribs 24 of the main rim. As a consequence, the demountable rim 25 cannot creep circumferentially of the felly 1. The ring 8 is advanced by the action of 10 the spring 11, circumferentially, in the direction of the arrow A, until the inclined edge 10 of the lug 9 co-operates with the inclined end 28 of the rib 27 and, consequently, the demountable rim cannot be slid crosswise of 15 the felly 1. The wedge 90 is engaged in the recess 92 and consequently any looseness in the demountable rim, in a direction parallel to the median plane of the wheel, is taken up. When it is desired to remove the demountable rim 25 from the felly, the following operation is carried out:—

By means of the squared end 18, the shaft 16 is rotated, and the pinion 15 on the shaft 16, meshing into the rack 14 on the ring 8, 20 rotates the ring 8 in the direction of the arrow B, until the lug 9 on the ring 8 is out of engagement with the end of the rib 27 on the demountable rim 25. When the ring 8 is rotated in the direction of the arrow 25 B, as above described, the spring 11, bearing against one end of the lug 9, is put under tension. When the ring 8 is rotated in the direction of the arrow B, the dog 18, under the action of the spring 19, engages in the 30 notch or seat 53 in the ring 8. A reverse rotation of the ring 8 in the direction of the arrow A, under the action of the spring 11 is, therefore, prevented. When the ring 8 is rotated in the direction of the arrow B, 35 the lug 9 first clears the end of the rib 27 on the demountable rim 25. Then the arm 31 of the lever 29 is engaged by the projection 33 on the ring 8. The lever 29 is tilted on its fulcrum 36, and the arm 30 of the 40 lever, engaging the projection 35 on the demountable rim 25, starts the demountable rim transversely of the felly 1. The demountable rim 25 may then be slid entirely off the felly 1 by hand, and when this operation 45 is carried out, the projection 35 on the demountable rim passes through the slot 34 in the flange 3 on the felly 1.

The dog 18 may be pushed inwardly by pressure exerted against the button 20, and 50 when the dog 18 moves out of the notch or seat 53, the ring 8 is free to move in the direction of the arrow A, under the action of the spring 11.

Having thus described the invention, what 55 is claimed is:

1. In a device of the class described, a felly; an auxiliary rim having a transverse rib; means on the felly for engaging the rib to prevent the auxiliary rim from creeping 60 on the felly; mechanism for holding the

auxiliary rim from moving transversely of the felly, said mechanism comprising a locking member mounted to slide on the felly circumferentially of the felly and having a projection engaging the end of the rib, a lever fulcrumed intermediate its ends on the felly, spaced projections on the locking member, and coacting one at a time with one end of the lever, and a projection on the auxiliary rim, and coacting with the other end 75 of the lever.

2. In a device of the class described, a felly; an auxiliary rim having a transverse rib; means on the felly for engaging the rib to prevent the auxiliary rim from creeping 80 on the felly; mechanism for holding the auxiliary rim from moving transversely of the felly, said mechanism comprising a locking member mounted to slide on the felly circumferentially of the felly and having a projecting lug engaging the end of the rib, the lug and said end of the rib being mutually inclined, spring means for moving the locking member in one direction to cause the lug to engage the end of the rib, and means 85 under the control of an operator for moving the locking member in an opposite direction, to disengage the lug from the end of the rib.

3. In a device of the class described, a felly; an auxiliary rim having a transverse rib; means on the felly for engaging the rib to prevent the auxiliary rim from creeping 90 on the felly; mechanism for holding the auxiliary rim from moving transversely of the felly, said mechanism comprising a locking member mounted to slide on the main rim circumferentially of the main rim and having a projecting lug engaging the end of the rib, the lug and the end of the rib being 95 mutually inclined, spring means for moving the locking member in one direction to cause the lug to engage the end of the rib, a latch slidable on the felly transversely thereof and engaging the locking member to hold the locking member retracted against the action of the spring means, the latch including a manipulating part disposed exteriorly of the felly, and means under the control of an operator for moving the locking member in an opposite direction, to disengage the lug from the end of the rib, against 100 the action of the spring means.

4. In a device of the class described; a felly; an auxiliary rim having a transverse rib provided at one end and on its under edge with a recess; means on the felly for engaging the rib to prevent the auxiliary rim from creeping 105 on the felly; mechanism for holding the auxiliary rim from moving transversely of the felly, said mechanism comprising a locking member mounted to slide circumferentially of the felly, the locking member having a projection engaging one end face of the rib, the projection and 110

125

130

said end face of the rib being mutually inclined to crowd the auxiliary rim transversely of the felly, the projection having a lateral wedge engaged in the recess, the 5 wedge being inclined circumferentially of the felly to expand the auxiliary rim circumferentially.

In testimony that I claim the foregoing as my own, I have hereto affixed my signature in the presence of two witnesses.
